(57) CLAIM

The ornamental design for a small animal exercise ball, as shown and described.

DESCRIPTION

FIG. 1 is a top perspective view of the small animal exercise ball showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan elevation view thereof; and,

FIG. 7 is a bottom plan elevation view thereof.

The broken lines shown on the drawings are for the purpose of illustrating environmental structure and forms no part of the claimed design.
